CONTROL DEVICE

Philip S. Russel, Detroit, Mich., assignor to Detroit Lubricator Company, Detroit, Mich., a corporation of Michigan

Application March 24, 1943, Serial No. 480,341

5 Claims. (Cl. 103—26)

This invention relates to new and useful improvements in liquid level control devices and more particularly to such a device which is fed by a motor driven pump and which is particularly adapted for supplying liquid fuel to a fluid fuel burner.

An object of the invention is to provide safety means for limiting the supply of liquid to a chamber supplied by the pump in the event the operation of the pump is not stopped upon the occurrence of a desired liquid level in the chamber.

Another object is to provide a single operating means for controlling the operation of the pump and of the safety liquid level control means.

The invention consists in the improved construction and combination of parts to be more fully described hereinafter and the novelty of which will be particularly pointed out and distinctly claimed.

In the accompanying drawing, to be taken as a part of this specification, there is fully and clearly illustrated a preferred embodiment of the invention, in which drawing the figure is a view in vertical central section with certain parts in side elevation of a liquid level control device embodying the invention.

Referring to the drawing by characters of reference, 1 designates generally a casing or container having a liquid chamber 2 having an inlet 3 communicating and registering with the inlet of a pump 4, preferably of the gear type. The pump 4 is secured by bolts or screws 5 in sealing engagement with a boss or pad extending upward into the chamber 2 from the chamber bottom wall 6. The outlet 7 from the pump 4 discharges into the chamber 2 below the liquid level therein. A drive shaft 8 for the pump extends upward through an aperture in the cover member 9 of the casing and is connected to the armature of an electric motor 10 mounted externally of the chamber 2 and on the cover member 9. The motor 10 is controlled by a switch 11, preferably of the snap acting type, having an operating plunger 12 which moves the switch to closed position upon inward movement. The motor 10 is supplied with current through lead wires or conductors 13, 14 of which the conductor 14 connects to one terminal of the switch 11. From the other terminal of the switch 11 a lead wire or conductor 15 connects to the motor 10 to complete the motor circuit. The switch 11 is preferably mounted upon the cover member 9 externally of the chamber 2 by means of a cover bracket 16. The switch operating thrust member 12 is actuated by a cam 17 carried by a reciprocal

thrust member or operating rod 18 which extends upward from the chamber 2 through a guide aperture 19 in the cover member 9. The rod 18 is pivotally connected, as at 20, to a float or liquid level responsive member 21 which is supported by a pivoted arm 22. In the chamber 2 there is a supporting post 23 extending upward from the bottom wall 6 and to which the arm 22 is pivotally connected, as at 24.

10 Leading from the chamber 2 below the normal liquid level therein, designated by the line L—L, and through an outlet fitting 25, there is an outlet conduit 26 having an upward facing valve seat 27 controlled by a vertically reciprocal safety valve member 28 which is guided for longitudinal reciprocation by a cap member 29 mounted on the fitting 25. The stem of the valve member 28 extends upward adjacent the float arm 22 and is operatively connected thereto by a lost motion connection comprising a pin 30 projecting from the valve stem and extending into a vertical slot 31 in the arm 22. This pin and slot lost-motion connection is such that the lost-motion is not taken up so as to lift the valve member 28 from its seat 27 until there is upward movement of the float 21 beyond its upward movement which opens the switch 11. The conduit 26 connects into the inlet strainer chamber 32 which supplies the pump inlet conduit 3 so that the conduit 26 and the strainer chamber 32 together provide a bypass conduit leading from the liquid chamber 2 to the pump inlet. The strainer chamber 32 has an inlet passage 33. The inlet passage 33 is provided with a check valve 35 which closes 35 against back flow from the chambers 2 and 32 to the supply pipe or conduit 34.

The chamber 2 has an outlet 36 controlled by a manually operable metering valve 37. Leading from the outlet 36 there is a pipe or conduit 38 for connection to the point of use of the liquid in chamber 2 such, for example, as a fluid fuel burner.

The operation of this device is as follows. The parts are shown in a position in which the pump 4 has just been stopped from further drawing of liquid fuel through the supply pipe 34 and discharge of the same through the outlet 1 into the chamber 2. Accordingly, the float 21 has moved upward so that the cam member 17 has permitted the plunger 12 to move outward and open the switch 11, thereby to stop the motor 10. Now, upon supply of the liquid fuel from the chamber 2 through the metering valve outlet 36, the float 21 will move downward and the cam member 17 will move the switch operating

plunger 12 inward to close the switch 11, thereby starting the motor 10 and the pump 4. The liquid level in the chamber 2 will be maintained substantially constant at the line L—L by reason of the starting and stopping of the pump 4 by the float 21. If the float operation, upon the occurrence of the desired predetermined liquid level, fails to stop operation of the motor 10 for any reason, so that the liquid level continues to increase in the chamber 2, then this further increase of liquid will cause a continued upward movement of the float 21. Since the lost-motion between the pin 30 and the lower end of the slot 31 is taken up substantially simultaneously with the operation of cam member 17 to open the switch 11, any further upward movement of the float 21 will lift the valve member 28 from its seat. Opening movement of valve member 28 will open the by-pass conduit from the chamber 2 to the pump inlet 3 so that there will be a recirculation of liquid from and to the chamber 2 through the strainer chamber 32. The liquid level in chamber 2 will now be maintained between the level L—L and the slightly increased level at which valve member 28 is opened, because when the discharge of liquid from the chamber 2 through the metered outlet 36 lowers the level in the chamber 2 such that the valve member 28 seats, then the pump 4, which under these circumstances is under continuous operation, will draw liquid fuel from the supply conduit 34 until the level again reaches the point in chamber 2 at which the valve member 28 will be opened.

What is claimed and is desired to be secured by Letters Patent of the United States is:

1. A liquid level controlling device, comprising a casing having a chamber with an outlet, a motor driven pump for discharging liquid into said chamber for flow therefrom through said outlet, a float lifted by liquid level increase in said chamber and operative at two liquid levels, means to stop operation of said pump, means operable by lifting of said float to the lower of said levels to actuate said stopping means, a normally ineffective discharge conduit for flow of liquid from said chamber, means for overtravel lifting of said float with increasing liquid level upon failure of said pump to stop, means to render said conduit effective to discharge liquid from said chamber, and means operable by lifting of said float to the higher of said levels to actuate said last-named means so that liquid will be discharged from said chamber through said discharge conduit.

2. A liquid fuel supplying safety device, comprising a casing having a chamber with a submerged metered outlet for supplying fuel to a gravity fed burner, a motor driven pump for supplying liquid fuel to said chamber at a rate greater than the rate of flow through said outlet, means controlling operation of said pump, a float responsive to liquid level in said chamber and controlling said controlling means to maintain over said outlet a substantially constant liquid level in said chamber, means for movement of said float with and upon liquid level increase above said constant level, a conduit leading from below the constant liquid level in said chamber, a safety valve normally maintaining said conduit closed, said valve and conduit being operable to 70 discharge fuel from said chamber at a rate at

least equal to the rate of fuel supply by said pump, and means operable by said float at a liquid level slightly above said constant level to actuate said valve to maintain a substantially constant slightly higher liquid level over said outlet.

5. A device of the character described, comprising a casing having a chamber, a pump having its outlet discharging into said chamber, a conduit for supplying liquid to said pump, a motor for driving said pump, a switch controlling the operation of said motor, a float in said chamber and operable upon occurrence of predetermined liquid level to actuate said switch to stop said motor, a by-pass conduit leading from below said liquid level to said first-named conduit, a valve closing said last-named conduit, and lost-motion means for movement of said float relative to said valve in operating said switch and operable by said float acting through said lost-motion means to open said valve upon increase of liquid level above said predetermined switch operating level, said by-pass conduit and said valve when open having a capacity for liquid flow sufficient to satisfy the suction of said pump thereby to maintain a higher substantially constant liquid level.

4. A device of the character described, comprising a casing having a chamber, a pump having its outlet discharging into said chamber, a conduit for supplying liquid to said pump, a motor for driving said pump, a switch controlling the operation of said motor, a float supporting arm pivotally mounted in said chamber, a float responsive to liquid level in said chamber and carried by said arm, a thrust member operatively connecting said float and said switch, a conduit opening upwardly through the bottom wall of said chamber and having an upward facing valve seat, said last-named conduit being communicatively connected to said first-named conduit to supply liquid from said chamber to said pump, a longitudinally reciprocal valve member seating on said valve seat and closing said last-named conduit, and a lost-motion connection between said 45 arm and said valve member so that said float is operable to lift said valve subsequent to operation of said switch by said thrust member.

5. A device of the character described, comprising a casing having a chamber for liquid and having an inlet conduit opening upwardly through the bottom wall of said chamber, a pump mounted on said wall and having its inlet communicating with said chamber inlet conduit, said pump having an outlet discharging into said chamber, a motor 55 mounted on said casing and operatively connected to said pump, a switch mounted on said casing and controlling said motor, a float supporting arm pivotally mounted in said casing, a float mounted on said arm, means operable by said float to open said switch upon the occurrence of a predetermined liquid level in said chamber, a conduit connecting said chamber below said liquid level to said first-named conduit, a normally closed safety valve for said last-named conduit, and means operatively connecting said valve and said arm, said last-named means being operable upon occurrence of a liquid level above said predetermined level to open said valve.
